UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

SEWING-MACHINE.

1,306,605.

Specification of Letters Patent.

Patented June 10, 1919.

Application filed May 14, 1913. Serial No. 767,609.

To all whom it may concern:

Be it known that I, JAMES R. MOFFATT, a citizen of the United States, residing at Chicago, in the county of Cook, State of Illinois, 5 have invented certain new and useful Improvements in Sewing-Machines, of which the following is a description, reference being had to the accompanying drawing and to the figures of reference marked thereon.

10 The invention relates to new and useful improvements in sewing machines, and more particularly to sewing machines which are adapted for stitching an edging or the like to a body fabric.

15 An object of the invention is to provide a sewing machine having spaced needles and coöperating devices for laying connecting loops between the lines of stitching, with a trimming mechanism located in advance of 20 the needles for trimming and directing an edge of fabric between the needles, and also an edging guiding device which will guide an edging to the stitching mechanism in rear of the trimming blade, so that the 25 trimmed edge may be connected to the edging by covering stitches.

A further object of the invention is to 30 provide a device of the above character with a guard or guide for directing the trimmed-off strip away from the stitching mechanism, which guard or guide may be readily moved away from the trimmer to give access to the parts of the stitching mechanism and the trimming mechanism in rear thereof.

35 These and other objects will in part be obvious, and will in part be hereinafter more fully disclosed.

In the drawings, which show by way of 40 illustration one embodiment of the invention,

Figure 1 is a front view of a machine having my improvements applied thereto;

Fig. 2 is a plan view showing the work support, the presser foot, the needles, the 45 trimmer blade, the edge guide and the relative arrangement of the same;

Fig. 3 is a perspective view showing the arrangement of the same parts;

Fig. 4 is a vertical sectional view through 50 the presser foot, the trimmer blade and the work support;

Fig. 5 is a detail in perspective showing the trimmer-operating mechanism; the needles and the looper;

55 Fig. 6 is a detail in perspective showing

the work support, the throat plate, the strip guide and also the needles;

Fig. 7 is a detail showing an edging attached to a fabric.

In the drawings, I have shown a sewing 60 machine which consists of a bed plate 1 carrying an overhanging arm 2, on which is pivoted a needle lever 3. This needle lever is vibrated from an eccentric strap 4 coöperating with an eccentric on the main shaft 5. 65 A needle bar 6 at the forward end of the overhanging arm is connected to the needle lever, and carries needles 7 and 8. A presser bar 9 mounted in the overhanging arm carries a presser foot 10 at the lower end 70 thereof.

Coöperating with the needles above the work support is a loop-laying finger 11. This loop-laying finger is mounted at the 75 lower end of a shaft 12, which is journaled in a sleeve 13, carried by a support 14. This support is mounted so as to slide back and forth in a bracket 15 carried by the head of the machine. The support is connected by a link 16 to a lever 17, which is oscillated 80 from an eccentric on the main shaft.

The shaft 12, at its upper end carries an arm which is connected to a link 18, and the link 18 in turn is connected to a lever 19, which is also oscillated from an eccentric 85 on the main shaft. These eccentrics for operating the levers 17 and 19 are so timed as to move the finger across the path of the needles, and then rearwardly, so that it is returned in a path entirely in rear of the 90 needles. In other words, the finger has substantially four motions.

The finger 11 at its free end is formed with a hook 20. When the needles 7 and 8 are raised, the hook is moved into engagement with the needle thread of the right hand needle, and forms a loop therein which is placed so that the left hand needle enters said loop, after which the finger is retracted from engagement with the needle thread, 100 and is moved or returned in a path in rear of the needles, as above noted.

These parts are substantially shown and described in the patent to R. G. Woodward, No. 679,660, granted July 30th, 1901, and 105 further detailed description thereof is thought unnecessary.

The shaft 12 is mounted so as to slide vertically in the sleeve 13. A spring 21 encircles the shaft, bearing against a collar 22 110

fixed to the shaft at the lower end thereof, and against the upper supporting sleeve at its upper end. This spring normally depresses the shaft 12, and holds the finger 11 5 in proper co-operative relation to the needles.

An arm 23 is mounted on the presser bar and extends underneath the collar 22 on the shaft 12. When the presser bar is raised, this arm engages the collar and lifts the 10 shaft 12, thus raising the finger 11. The finger 11 at its free end lies over the presser foot and is so positioned as to move close to the upper face of the presser foot. The spring for holding the shaft depressed and 15 the arm 23 for raising the same, permits the finger to be positioned as stated, and to be raised with the presser foot when the fabric is inserted in the machine.

Located in front of the stitching mechanism 20 is a trimming mechanism which consists of an upper movable blade 24 and a lower fixed or stationary blade 25. The fixed blade is carried by the throat plate 26 of the machine, and is secured thereto in any 25 suitable way. The upper movable blade 24 is carried by an arm 27, which is mounted on a support 28 consisting of spaced sleeves 29 and 30, which slide on guiding posts 31 and 32. The support is moved up and down 30 on the guiding posts by a lever 33. This lever is formed with a cylindrical rib at the free end thereof which engages a forked arm 34 carried by the support for the trimmer blade.

The lever at its rear end is pivoted to a fulcrum post 35. Said lever intermediate its 35 ends is forked, and engages an eccentric 36 on the main shaft 5. As the shaft rotates, the lever will be oscillated, moving the support 40 for the trimmer blade up and down on the guiding posts, which will cause the trimmer blade 24 to move vertically in the same path as it performs its trimming function. This trimming blade 24 is located directly 45 in front of the needle 8, so that the trimmed edge of the body fabric will pass between the needles 7 and 8.

The presser foot 10 extends in front of the trimming member, and is formed with a 50 rearwardly projecting and downwardly extending guiding member 37 for the trimmed-off strip. This guiding member deflects the strip downwardly against the strip guide 38. The strip guide 38 is mounted on a bracket 39 pivoted to the under side of the work support. Said bracket is formed with a vertical wall 40, which prevents the strip 55 from being deflected laterally underneath the work support. The strip guide at its upper end is curved upwardly and forwardly to insure the trimmed-off strip being bent downwardly and guided to the forward part of the machine. This guiding member on the presser foot and the strip guide carried 60 by the work support, insures the directing 65

of the trimmed-off strip away from the parts of the stitching mechanism. The bracket supporting the strip guide is pivoted, so that said strip guide may be swung away from the stitching mechanism and trimming 70 mechanism to give access to the parts thereof in rear of the strip guide.

From the above description, it will be noted that I have provided a sewing machine wherein a strip of fabric is trimmed and the 75 trimmed edge is guided between the spaced needles of the sewing mechanism, while the trimmed-off edge is directed away from the stitching mechanism.

In order that an edging may be guided so 80 as to be secured to the trimmed edge of the body fabric, I have provided an edging guide, which consists of a roller 41 mounted in suitable supporting lugs 42 and 43, carried by the presser foot 10. The presser foot 85 10 is formed with a laterally projecting arm 44, which supports the lug 43. This guiding roller is disposed directly in front of the needles, and is substantially parallel with a line or plane passing through the needles. 90 Said roller is also located directly over the rear end of the trimming blade 24, so that an edging strip passing over the roller may be led to the needles in rear of the trimming point. 95

The roller 41 is preferably provided with spaced notched disks 45, which are adapted to engage the edging between the cross bars thereof and facilitate the guiding of the same. The presser foot is also provided with 100 a guard plate 46, which is curved laterally to give sufficient room for the movement of the loop-laying finger 11. This guard plate extends vertically, and protects the operator from both the loop-laying hook or finger 105 and the needles.

In Fig. 7 I have shown a body fabric F, which is preferably formed of knit material, the edge of which has been trimmed and an edging E secured thereto by stitches S. This 110 edging is guided by the roller, as above noted, and placed relative to the trimmed edge of the body fabric, so that one needle will pass through the edging while the other needle passes through the body fabric. The 115 lines of stitching formed by the needle are connected above the fabric by the loop-laying finger 11, which carries one needle thread into the path of the other needle, and by the looper threads which engage the 120 needle loops beneath the material and join the same.

From Fig. 5 of the drawing it will be noted that the operating member 33 for the trimming device extends underneath the 125 looper 47, while the looper carrier 27 on which the blade 24 is mounted is in front of the needles 7 and 8 and the looper 47. In other words, by the construction above described, I have provided a trimmer-operat- 130

ing mechanism wherein the trimmer is moved positively up and down from a main shaft underneath the work support, and at the same time provided ample space for the 5 operation of the looper which coöperates with the needles beneath the work support.

It is obvious that minor changes in the details of construction and arrangement of parts may be made, without departing from 10 the spirit of the invention.

Having thus described my invention, what I claim as new and desire to secure by Letters Patent, is:—

1. The combination of stitch-forming 15 mechanism including spaced needles and devices for laying connecting loops between the needles, of a trimming mechanism having a trimmer blade located beneath the work support and projecting above and 20 overhanging the work support directly in front of said needles, a presser foot, an edging guide carried by the presser foot and located directly above the trimmer blade, 25 whereby an edging may be guided to the stitching mechanism in rear of the trimming point.

2. The combination with stitch-forming mechanism including spaced needles and devices for laying connecting loops between 30 the needles, of a trimming mechanism having a trimmer blade located directly in front of one of the needles, whereby the trimmed edge passes between the needles, a presser foot, and an edging guide, consisting of a 35 roller carried by said presser foot and located directly above the trimmer blade, whereby an edging may be guided over said roller to the stitching mechanism in rear of the trimming point.

40 3. The combination with stitch-forming mechanism including devices for forming connected rows of stitching, a presser foot, an edging guide roller carried by said presser foot in front of the needles of the stitching mechanism, and a trimming mechanism including a trimming blade supported beneath the work support and projecting above and overhanging the work support, said trimming blade being located in advance 45 of the stitching mechanism.

45 4. The combination with stitch-forming mechanism including a plurality of spaced needles, a device for guiding an edging to said needles, a trimming mechanism located 50 in advance of the needles and so arranged that the trimmed edge is guided between the needles and including a trimming blade sup-

ported beneath the work support and extending above and overhanging said work support, said trimming blade being also disposed underneath the guiding means for the edging, and a strip guide for deflecting the trimmed-off strip away from the stitching mechanism.

5. The combination with stitch-forming 60 mechanism including a plurality of spaced needles, a device for guiding an edging to said needles, a trimming mechanism located in advance of the needles and so arranged that the trimmed edge is guided between the 65 needles and including a trimming blade supported beneath the work support and extending above and overhanging said work support, said trimming blade being also disposed underneath the guiding means for the 70 edging, a presser foot, said presser foot having means for deflecting the trimmed-off strip, and a strip-guiding device for guiding the trimmed-off strip away from the 75 stitching mechanism.

6. The combination of a stitch forming 80 mechanism including spaced needles and devices for laying connecting loops between the needles, a trimming mechanism including coöperating trimming blades disposed in advance of the needle and an edging guide located in advance of the needle and having its edging guiding portion directly above the trimming blades, whereby an edging 85 passing over said edging guide may be directed in rear of the trimming blades and to the stitching mechanism without being 90 trimmed.

7. The combination with stitch-forming 95 mechanism including a needle, a presser foot, a trimming mechanism, an edging guide roller carried by the presser foot and located rearward of the cutting portion of the trimming mechanism and in advance of the needle, said guide roller being raised 100 from the bottom of the presser foot, whereby a fabric passing over the trimming blades may engage said guide roller, said presser foot being cut away in front of the needle and in rear of the guide roller to provide 105 a space for the fabric engaging said guide roller.

In testimony whereof, I affix my signature, in the presence of two witnesses.

JAMES R. MOFFATT.
